UNITED STATES PATENT OFFICE.

ALBERT HEWITT BORLAND, OF GEBO, WYOMING.

BEDCOVER SUPPORT.

Application filed July 6, 1925. Serial No. 41,823.

A great number of persons are annoyed by the pressure of the bed clothing. It is, of course, essential that the sleeper be protected in his bed from drafts and exterior atmosphere, so the use of bed clothing is an absolute necessity. It may therefore, be considered the object of this invention to provide warmth and comfort to persons occupying a bed, but at the same time relieve such persons from pressure of the bed covers.

It is a further object to provide a means which may be attached to any bed construction and which may be adjusted by the occupant of the bed, the said means having a gripping engagement with the center of the bed clothing, so that the same may be elevated to a tent-like position and only the inner edge portions thereof being contactable by the neck portions of the occupants of the bed, the remaining edges of the bed clothing being arranged in the usual manner between the mattress and the spring thereof.

It is a still further object to provide a means for centrally raising the bed clothing for a bed and which is of such construction as to support certain of the bed clothing when folded thereover, so that the temperature of the occupant of the bed may be nicely regulated, as for instance, should the occupant find that he is employing too little covering, another of the folded blankets or other coverings may be brought off of its support to bed covering position.

To the attainment of the foregoing, the invention consists in the improvement as hereinafter described and definitely claimed.

In the drawings:—

Figure 1 is a perspective view illustrating one form of the invention.

Figure 2 is a similar view illustrating a second form.

Figure 3 is a fragmentary perspective view looking toward the center of the strap employed and the adjustable bed clothing holder, which is associated with the strap.

Figure 4 is a similar view illustrating a modified form of bed clothing holder and the means for securing the same on the strap.

Figure 5 is a perspective view of a clamp for the strap which is employed when the device is used upon bedsteads having solid head and foot boards.

Figure 6 is a perspective view of the center of one of the bed clothings showing the eye through which the support passes.

Figure 7 is a perspective view of one of

the hooks employed in the construction illustrated in Figure 1.

Figure 8 is a view of the second hook employed in the said construction. 60

As disclosed by Figure 6 of the drawings the bed clothings 1 have their central portions provided with button-holes 2. Through these button holes there is passed a shank 3 centrally formed upon a member having 65 opposite loops 4. The loops, of course, underlie the bed clothings. The shank 3 is offset and extended to provide a substantially U-shaped hook 5. This hook is designed to be passed through any pair of oppositely 70 arranged spaced eyes or openings 6 on a yieldable strip 7 that is centrally stitched or otherwise secured to a strap 8. The strap 8, adjacent to its ends, has its underface provided with buckles or clasps 9 which adjustably engage the said ends of the said strap. These ends, for distinction, are indicated by the numeral 11'. 75

The looped ends of the strap 8 are designed to be passed around the upper members of the head and foot boards of a bedstead 10. By adjusting the ends of the strap, the strap proper may be arranged at any desired inclination between the head and foot board, and when the hook carrying loop 5 80 engages through the apertures 6 in the strip 7 the center of the bed clothings will be elevated to a tent-like position as illustrated in Figures 1 and 2 of the drawings.

It is of course, to be understood that the 85 sides and outer edges of the bed clothing are snugly tucked between the mattress and the springs, and it will be obvious that the occupant of the bed only has the inner edge of the bed clothing contacting with his person. 90 Thus the occupant of the bed is relieved of pressure of the bed clothing and his person is subjected to a circulation of warm air in his tent-like enclosure. 95

Any number of bed clothings may be 100 employed, and when the occupant finds that certain of these may be dispensed with he merely folds the exterior and useless clothing over the strap. Again should he find that additional bed clothing is required he 105 can move the same off of the strap over the remaining bed clothings.

In Figure 1 of the drawing, the strap 8 is engaged at the central portion thereof by a substantially U-shaped hook 11. This 110 hook has an upper eye end to which is attached a cord 12. The cord is trained over

a sheave wheel 13 secured to the ceiling in the bedroom directly above the bed. The free end of the cord is attached to an eye 14 formed on a member 15 which is preferably of wire and which is bent at determined intervals to provide spaced U-shaped hook portions 16. Any of these hooked portions may be brought over the top member of the head board of the bedstead, and in this manner the elevation of the bed clothing may be easily sustained and accurately determined.

The strip 7, while preferably of leather, may, of course, be constructed of any other material, as for instance, the said strip may be of metal. The strip in the center thereof is provided with a substantially rectangular opening for an eyelet 17. The eyelet may receive therethrough an eye 18 formed centrally on a member provided with oppositely extending loops 19, similar to the loops 4. The eye may have passed therethrough a spring actuated pin 20, similar to an ordinary safety pin, if desired, but in the construction illustrated in Figure 4, the body portion 21 of the pin has its outer end bent to form a dog 22 having its lower inner arm formed with an extension 23 that is also bent to provide a hook 24 for the pin 20. The pin is looped or coiled at its connection with the straight body 21.

In Figure 5 I have illustrated a means whereby the strap 8 may be attached to the head and foot boards of wooden bedsteads. The supporting means is preferably constructed from a single strand of wire to comprise parallel arms 25 that have their ends

rounded downwardly to provide substantially U-shaped jaws 26. The jaw portions are enclosed in compressible faces 27 so that the same will not inflict injury to the bedstead.

It is believed the simplicity of my construction and its advantages will be apparent. While I have illustrated a satisfactory embodiment of my improved device my features of invention are capable of extended application and I do not wish to be limited to the specific structure shown and described.

Having described the invention, I claim:

Means for raising the central portion of bed clothes above a bed, wherein each piece of bed clothing is provided with a central opening, said means comprising a member formed from a single piece of material and including oppositely extending loops adapted to be arranged beneath the innermost piece of clothing, a shank rising from said loops and adapted to be passed through the openings in said clothing, a substantially inverted U-shaped member formed with the shank and offset therefrom, a strap formed with adjustable loops adapted to be attached to the head and foot boards of the bed, and a yieldable strip arranged centrally of said strap and having spaced openings to receive the U-shaped member for the purpose specified.

In testimony whereof I affix my signature.

ALBERT HEWITT BORLAND.
